DESIGN FOR A METALLIC GRILL

Albert J. Fitzgerald, Braintree, Mass.

Application January 16, 1936, Serial No. 60,619

Term of patent 14 years

To all whom it may concern:

Be it known that I, Albert J. Fitzgerald, a citizen of the United States, residing at Braintree, in the county of Norfolk and State of Massachusetts, have invented a new, original, and ornamental Design for Metallic Grills, of which the following is a specification, reference being had to the accompanying drawing, forming part thereof.

The figure is a plan view of a metallic grill showing my new design.

The grill comprises a perforated sheet of metal in combination with longitudinally and transversely arranged metal bars, certain of the bars being placed on one side of the sheet and the remaining bars on the opposite side of the sheet.

I claim:

The ornamental design for a metallic grill, as shown and described.

ALBERT J. FITZGERALD.
